UNITED STATES PATENT OFFICE.

DE WITT H. WYATT, OF COLUMBUS, OHIO, ASSIGNOR TO THE WYATT ENGINEERING COMPANY, OF COLUMBUS, OHIO, A CORPORATION OF OHIO.

APPARATUS FOR FORMING PIPE-JOINTS.

1,352,571.

Specification of Letters Patent. Patented Sept. 14, 1920.

Application filed December 23, 1918. Serial No. 267,924.

To all whom it may concern:

Be it known that I, DE WITT H. WYATT, a citizen of the United States, residing at Columbus, in the county of Franklin and State 5 of Ohio, have invented certain new and useful Improvements in Apparatus for Forming Pipe-Joints, of which the following is a specification.

This invention relates to an apparatus for 10 forming pipe joints such as disclosed in my patent granted November 12, 1918, No. 1,284,334.

In the present invention, it is my main object to provide a structure which is adjustable to accommodate pipes of varying 5 diameters, or in other words, to make a single form structure accommodate a number of sizes of pipes. To do this, I provide a plurality of sections each in themselves 0 formed of a plurality of members flexibly joined together, in combination with means for detachably uniting said sections at various points to adapt the assemblage to pipes varying in size.

It is also an object of the present invention to provide a structure of the class described wherein the form may be adjusted to accommodate a number of pipes of varying standard size in combination with a second adjustment to adjust the assemblage to such slight variations in size as occur in the so called standard sizes. These latter variations may result from a number of causes, notably variations in shrinkage during the 5 manufacture of the pipes.

The preferred embodiment of my invention is shown in the accompanying sheet of drawings wherein similar characters of reference designate corresponding parts and 10 wherein—

Figure 1 is a view in side elevation showing my improved apparatus applied to a pipe.

Fig. 2 is a top plan view on an enlarged scale of the upper portion of the structure shown in Fig. 1.

Fig. 3 is an enlarged sectional view taken through one edge of the flexible members showing the manner in which the various sections are joined to adapt the form to various standard sizes, and

Fig. 4 is a horizontal longitudinal section taken through the structure shown in Fig. 1.

I have chosen to illustrate my invention in connection with the bell end 1 of a pipe 2

and the spigot end 3 of the pipe 4. In using the form, the bell and spigot ends of the pipes are assembled as shown in Fig. 4 and the form then applied thereto in the manner shown in Fig. 1. Cement or any other suitable material is allowed to run around the form to suitably pack the same as is illustrated at 5.

The form itself is in general constructed after the manner described and claimed in my patent referred to and comprises, in the present instance, two sections 6 and 7, each section being in itself formed of a plurality of form members 8 of short length and flexibly joined together by means of the flexible cables shown at 9. The present embodiment shows the various members 8 as being provided with struck out portions 10 adjacent each longitudinal edge through which the cables 9 are laced and by a hammer blow upon these portions 10 after the cables have been properly applied, they may be rigidly held in connection with each of the various form members. As is illustrated in Fig. 1, the section 6 is constituted of a plurality of form members 8 ending with that designated 11 at one end and carries an upstanding plate 12 at its opposite end which co-operates with a portion 13 to form a funnel through which the sealing 85 material may be poured. This portion 13 forms one end of the section 7 whose opposite end terminates with the member 14 and the clamps 15, the latter being shown particularly in Fig. 3. The funnel portion 90

13 is mounted upon a form member 16 which is adjustably carried upon the corresponding end of the section 7 to float as is illustrated in my former patent, or, if desired, this latter form 16 may be 95 entirely free of the remainder of the section 7 and be placed in position by hand. It is essential that one end of one of the sections 6 and 7 should be provided with a small adjustment and this may be accomplished by mounting the funnel portion and its supporting member as described when used in combination with the tightening clamps 17. These tightening clamps are 100 pivotally mounted adjacent the end of the section 7 as is shown at 18 and it is to the member carrying these clamps that the cables 9 are rigidly secured at one end. The member carrying the funnel portion 12 on the end of the opposite section 6 is provided 105 110

with a pair of upstanding lugs 19 with which the ends of the adjusting screws 20 threaded through the clamps 17 abut. Likewise, the cables 9 of the section 6 also end 5 with the form member carrying a funnel portion 12. Thus, when the form is placed about the meeting ends of a pair of pipes, it may be tightened in position by means of the screws or bolts 20 and in this tightening 10 operation, the form member 16 carrying the funnel portion 13 telescopes beneath the end form member of the section 7 a distance corresponding to any variations in the circumference of the so called standard pipes. By 15 this arrangement, this small adjustment member effected and at the same time the funnel portion will be presented to permit the easy pouring of the sealing mixture.

In order to adapt the structure to different sizes of standard pipes, the opposite end 20 of the section 7 is provided with the clamp 15 of which the screw 21 forms a portion. The cables 9 of the section 7 are rigidly secured to these clamps and then these clamps may be 25 brought into holding engagement with a portion of the cables 9 passing over any one of the form members 8 of the section 6 and tightened in such position by means of the screws 21 as is illustrated particularly 30 in Fig. 3. From this figure, it will be apparent that only one struck out portion 10 is provided on each form member for each cable and that these various form members are overlapped slightly as is shown at 22. 35 Because of this, the end member 14 of the section 7 may be inserted between the overlapping ends 22 of any of the form members 8 of the section 6, the cables 9 being permitted to pass through the space between 40 these overlapping ends when the end members are flexed outwardly after the manner shown in connection with the member 11 in Fig. 3. Thus it will be apparent that the section 7 may be secured to the section 6 at a 45 point between any of the overlapping ends of the form members 8 by simply properly applying the clamps 15 in connection with the cables 9.

From the foregoing description, taken in 50 connection with the accompanying sheet

of drawings, it will be apparent that I have provided a form of structure capable of two adjustments, one being to adapt the form to various sizes of standard pipes and the other being to adapt the form to those slight 55 variations in circumference found in pipes of the same standard size. From this it will be apparent that a great saving in initial outlay is rendered possible.

What I claim is:

1. In an apparatus for forming pipe joints, a plurality of sections each in themselves formed of a plurality of separable members flexibly joined together, and means 60 for detachably uniting said sections at various points to form an annular form.

2. In an apparatus for forming pipe joints, a plurality of sections each in themselves formed of a plurality of separable members flexibly joined together, and means 70 for detachably uniting one end of one section between any of the members of another section.

3. In an apparatus for forming pipe joints, a plurality of sections each in themselves formed of a plurality of separable members flexibly joined together, means for detachably uniting one end of one section between members of another section to approximately present the desired size, means 75 for joining the ends of the previously connected sections together about the meeting ends of a pair of pipes, and additional means whereby the assembled members may be given a final adjustment as to size to 80 properly fit said pipes.

4. In an apparatus for forming pipe joints, a plurality of sections each in themselves formed of a plurality of separable members flexibly joined together by means 90 of flexible cable, a clamp structure carried by one end of at least one section for detachable connection with the cable on the adjoining section, and means for tightening said sections in position about the meeting 95 ends of a pair of pipes.

In testimony whereof I affix my signature.
DE WITT H. WYATT.

Witness:
C. C. SHEPHERD.
